Primary Examiner — Jack Reickel*Assistant Examiner* — Salamah Jordan(74) *Attorney, Agent, or Firm* — Daniel M. Cohn;
 Howard M. Cohn(57) **CLAIM**

The ornamental design for a balloon frame, as shown and described.

DESCRIPTION

FIG. 1 is a perspective view of a balloon frame, showing my new design;

FIG. 2 is a front elevation view thereof; the rear elevation view being the same;

FIG. 3 is a left side elevation view thereof; the right side elevation view being the same;

FIG. 4 is a top plan view thereof;

FIG. 5 is a bottom plan view thereof; and,

FIG. 6 is an enlarged view of the circled portion of FIG. 1. The broken lines represent environment and form no part of the claim.
